UNITED STATES PATENT OFFICE.

WALTER B. McMILLEN, OF SAN FRANCISCO, CALIFORNIA.

WATCH-HOLDER.

1,362,498.

Specification of Letters Patent. Patented Dec. 14, 1920.

Application filed December 10, 1918. Serial No. 266,103.

To all whom it may concern:

Be it known that I, WALTER B. McMILLEN, a citizen of the United States, residing at San Francisco, in the county of San Francisco and State of California, have invented new and useful Improvements in Watch-Holders, of which the following is a specification.

This invention relates to new and useful improvements in watch holders and the principal object of the invention is to provide a case for the watch provided with a vacuum cup for holding the case to flat surfaces by suction.

15 The device is more particularly adapted for use by motormen on street cars, automobileists, engineers, aviators and all other persons desiring to have a watch in full view and which may be held in a position adjacent the driver's seat or stand.

20 Another object of the invention is to provide a device of this character which is simple and durable in construction, reliable and efficient in operation and one which can be manufactured and placed upon the market at a minimum cost.

The invention also consists in certain other features of construction and in the combination and arrangement of the several 30 parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a view of the device applied to a watch.

Fig. 2 is a sectional view of the device alone.

Fig. 3 shows the device secured to a flat surface.

45 In these views 1 represents the case which is made of rubber or any other suitable material and is adapted to be placed over the

watch. The case is provided with a front opening 2 so as to expose the dial of the watch and with a nipple 3 through which the stem of the watch passes. To the end part of the case is secured a cup 4 which is made of rubber. This cup is made in the form of the usual vacuum cup so that when pressed upon a surface a vacuum will be created in the cup so as to hold the device to the surface by suction. The cup may be secured to the case in any suitable way or it may be formed integral therewith. I sometimes find it desirable to place a small spring plate 5 in the bottom of the case to engage the bottom of the watch, so as to hold the watch against the front part of the case.

It will be seen that the watch may be held against a windshield of an automobile or the front window of a street car or may be placed against any flat surface and will be held there by the suction.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:—

A watch holder of the class described comprising a case made of a resilient material and adapted to be placed around the watch, said case having an opening therein to expose the dial of the watch, a nipple on said case through which the stem of said watch passes, a spring plate arranged on the bottom of said case to engage the bottom of said watch and hold same against the front part of said case, and a rubber vacuum cup secured to the case at one end thereof so that when pressed upon a surface a vacuum is created and holds the device to said surface by suction.

In testimony whereof I affix my signature.

WALTER B. McMILLEN.
